UNITED STATES PATENT OFFICE.

WILLIAM MCFARLAND, OF TRENTON, NEW JERSEY.

ROTARY ENGINE.

SPECIFICATION forming part of Letters Patent No. 615,037, dated November 29, 1898.

Application filed April 28, 1898. Serial No. 679,065. (No model.)

To all whom it may concern:

Be it known that I, WILLIAM MCFARLAND, a citizen of the United States, residing at Trenton, in the county of Mercer and State of New Jersey, have invented certain new and useful Improvements in Rotary Engines, of which the following is a specification.

My invention has relation to a rotary engine, and in such connection it relates more particularly to the construction and arrangement of such an engine.

The principal object of my invention is to simplify the construction and increase the efficiency of a rotary engine; and to that end my invention consists of a rotary engine constructed and arranged in substantially the manner hereinafter described and claimed.

The nature and scope of my invention will be more fully understood from the following description when taken in connection with the accompanying drawings, forming part hereof, in which—

Figure 1 is a longitudinal sectional view of a rotary engine embodying main features of my invention. Fig. 2 is a cross-sectional view thereof, and Figs. 3 and 4 are respectively side elevational views of a single and double cam arrangement for operating the slide or valve mechanism of the engine.

Referring to the drawings, the exterior casing A is preferably cylindrical, and it consists of the tubular piece or casting a, bolted or otherwise secured to the heads a'. Within the casing A rotates a cylindrical piston b, having at its ends the heads b', which project beyond the periphery b² of the piston and rest in close proximity to the interior of the tubular piece a, as clearly indicated in Fig. 1. Between the sides or heads b' of the piston and the sides or heads a' of the casing A is left, by preference, a small space, so as to reduce the frictional contact of the piston and casing to the surface of the rims b³ of the piston, which contacts with the tubular piece a. The rims b³ of the heads b' are united by a longitudinal cross-piece or projection b⁴, forming the abutting surface of the piston, against which the steam or propelling fluid is adapted to be directed.

Traversing the casing A longitudinally is a shaft d, which is free to rotate in the heads a' of the casing. To this shaft d is keyed or

otherwise secured the piston b. On the shaft d, outside the casing, is splined a double cam e, consisting of two collars e' and e², each carrying a cam projection e³, which, as shown in Fig. 4, are reversely arranged so far as their throw-surface is concerned.

The casing A is provided with two sets of live-steam inlets f and g and corresponding exhaust-outlets f' and g' for the steam or fluid, as illustrated in Fig. 2. Between these sets of inlets and outlets is arranged a slide or cut-off h, adapted to be raised and lowered in the interior of the casing by a rod or stem h', which reciprocates in a stuffing-box h², projecting from the tubular portion a of the casing. The rod or stem h' is carried by a curved bail h³, to the center portion of which it is securely bolted. The free ends or arms of this bail h³ are guided in bearings h⁴, secured to the heads a' of the casing. The springs h⁵, interposed between the bearings h⁴ and collars h⁶, formed on the ends of the bail h³, serve normally to depress the bail h³, the stem h', and the slide h. The ends of the bail are provided with rollers h⁷, adapted to rest upon the cam-surface of either collar e' or e², as desired, which cam-surface is adapted to elevate the bail.

In operation if the piston is to rotate in the direction shown by the arrow in Fig. 2 the inlet g and exhaust f' are closed by suitable valves (not shown) and the inlet f and exhaust g' are opened. The slide h in its normal position rests, as illustrated in Fig. 2, to the left of the abutting surface b⁴ of the piston and down upon the tubular surface of said piston and prevents steam or liquid entering through the inlet f from passing to the left of the slide. The fluid must therefore act upon the surface b⁴ and propel the piston in the direction indicated by the arrow. The piston being secured to the shaft d causes the same to rotate, and the shaft in turn causes the collars e' to rotate, and at the proper interval of time their throw-surface e³ impinges against the rollers h⁷ on the ends or arms of the bail h³. The bail is thereby elevated, and its center portion raises the slide h in an absolutely vertical plane, so as to permit the abutting surface b⁴ of the piston to pass, when the slide is immediately depressed by the springs h⁵, the rollers h⁷ passing at

that time off of the throw-surface e^3 of the collars. When the piston b is to travel in a reverse direction, the inlet g and exhaust f' are opened and the inlet f and exhaust g' are closed. At the same time the collars e' and e^2 are slid upon the shaft until the reverse cam-surface of the collars e^2 are brought under the rollers h^1 , when the operation will be the same as hereinbefore explained.

10 Since the arms and the center portion of the bail are guided in a vertical direction by, respectively, the bearings h^4 and the stuffing-box h^2 , the stem h' and slide h are elevated in an absolutely vertical plane without side 15 or angular movement, thus preventing the jamming of the slide in the casing.

Having thus described the nature and object of my invention, what I claim as new, and desire to secure by Letters Patent, is—

20 In a rotary engine, a cylindrical casing, a piston rotating therein, a shaft traversing the casing and secured to the piston, a double cam splined to the shaft outside the casing

and at either end of said shaft, in combination with a slide reciprocating in said casing, a stem 25 carrying said slide, a curved bail having its central portion secured to said stem, bearings located on both sides of said casing and adapted to receive and guide the free ends or arms of said bail, a collar formed on the extremity 30 of each arm and a spring interposed between each bearing and collar and adapted to normally depress said arms, said double cams having reversely-arranged throw-surfaces adapted to be shifted beneath the arms of 35 said bail and thereby to periodically elevate the arms of said bail against the tension of said springs, substantially as and for the purposes described.

In testimony wherof I have hereunto set 40 my signature in the presence of two subscribing witnesses.

WM. MCFARLAND.
